(57) **CLAIM**

The ornamental design for a three-dimensional tic tac toe game board, as shown and described.

DESCRIPTION

FIG. 1 is a perspective view of my new three-dimensional tic tac toe game board;

FIG. 2 is a front elevational view of the three-dimensional tic tac toe game board;

FIG. 3 is a rear elevational view of the three-dimensional tic tac toe game board;

FIG. 4 is a right side elevational view of the three-dimensional tic tac toe game board, the left side view being a mirror image thereof;

FIG. 5 is a top plan view of the three-dimensional tic tac toe game board; and,

FIG. 6 is a bottom plan view of the three-dimensional tic tac toe game board.

My three-dimensional tic tac toe game board is characterized by a sloping I-beam support and three decks spaced evenly along the axis of the I-beam.
